UNITED STATES PATENT OFFICE.

CARL R. SHAFER, OF DETROIT, MICHIGAN.

SAFETY EGG-CASE.

1,330,284.

Specification of Letters Patent. Patented Feb. 10, 1920.

Application filed January 25, 1919. Serial No. 273,016.

To all whom it may concern:

Be it known that I, CARL R. SHAFER, a citizen of the United States of America, residing at Detroit, in the county of Wayne 5 and State of Michigan, have invented certain new and useful Improvements in Safety Egg-Cases, of which the following is a specification, reference being had thereto in the accompanying drawings.

10 My invention relates to improvements in safety egg cases, the object of the invention being to provide a simple, inexpensive casing, which can be utilized for packing and shipping eggs, and is particularly designed 15 for transmitting through the mail, packages of a dozen or more eggs, utilizing the parcel post service.

A further object is to provide improvements of the character stated which can be 20 shipped flat to the farmer or shipper, and can be assembled by him as he packs the eggs for shipment.

A further object is to provide improvements of the character stated which not only 25 thoroughly protect the eggs from breakage, but also make provision for absorbing leakage from cracked eggs which may have been placed in the package by mistake.

With these and other objects in view, the 30 invention consists in certain novel features of construction and combinations and arrangements of parts as will be more fully hereinafter described and pointed out in the claims.

35 In the accompanying drawings:

Figure 1 is a broken perspective view illustrating my improvements;

Fig. 2 is a view in longitudinal section;

Fig. 3 is a view similar to Fig. 2 illustrating a modification;

Fig. 4 is a fragmentary plan view on a reduced scale of the egg partition, used in the construction shown in Figs. 1, 2 and 3;

Fig. 5 is a similar view of an egg partition, used in the construction shown in Fig. 6;

Fig. 6 is a view similar to Fig. 2 showing the use of two different egg partitions for engaging the large and small ends of the 50 eggs;

Figs. 7, 8 and 9 are views similar to Figs. 2 and 6, illustrating other modifications.

1 represents the body of the box, and 2 a cover fitting thereupon. The body 1 and

cover 2 are preferably of cardboard of the 55 folding or knock-down type, so that they may be shipped flat and occupy but relatively small space.

The cover 2 telescopes on the body 1 and provides at the four sides of the body, a double thickness of material throughout the egg space between the upper and lower partitions 3 and 4 respectively, which will be more fully hereinafter described.

The partitions 3 and 4 each comprises a 65 single piece of fairly heavy cardboard conforming in size to the interior dimensions of the body and spaced from the top and bottom of the receptacle by relatively thick layers of packing 5. This packing 5 may 70 consist of excelsior, shavings, sawdust, or other similar material which will absorb shocks and jars and also absorb the contents of broken eggs.

Said partitions, which are preferably duplicates, are provided with a suitable number of egg-engaging openings 6. These openings are formed by first producing incisions 7 at right angles to each other as shown in Fig. 4, and then bending the 80 tongues or fingers 8 formed by said incisions at an angle to the partition as shown clearly in Figs. 2 and 3.

These tongues 8, when the eggs are in the openings 6, form resilient or flexible partitions or spacers between the eggs having sufficient strength to hold the eggs properly spaced, and yet of sufficient elasticity or flexibility to compensate for various sizes and conditions of the eggs. Between the 90 partitions 3 and 4 are air spaces within which the tongues 8 permit a limited lateral movement of the eggs, whereby shocks or blows acting on the package are absorbed without damage to the eggs. Said 95 tongues also yieldably resist shocks acting axially of the eggs, such shocks being further cushioned by the layers of packing 5.

In assembling the package the lower layer of excelsior 5 is first positioned in the box 100 1, and the lower partition 4 is then located upon said layer. The eggs are then positioned in the openings 6 between the tongues 8. The next step is to position the upper partition 3 above the eggs with the upper 105 ends of the eggs projecting through the openings 6. The upper layer of excelsior is then positioned upon the partition 3, and

the cover 2 located on the box and secured by a string 12 or other suitable means.

In Fig. 2, I illustrate a single horizontal series of eggs, and Fig. 3 illustrates a receptacle provided with two series of eggs one above the other. In both instances I employ the same construction of partition with the corresponding arrangement of excelsior or packing, and except in the particulars noted, the packages are the same.

With my improved construction and arrangement of parts, the eggs are securely held and protected from blows from any direction.

15 As above stated, the cover 2 and the body 1 provide a double thickness of material all around the egg space, and as the eggs are all spaced from the outer wall or walls of the package, such blows cannot be imparted to the eggs. The layers of excelsior or other packing protect the ends of the eggs from blows or jars from above or below, and also serves the purpose of absorbing the contents of a cracked or broken egg, 20 hence preventing the disfiguring of the package in case a cracked egg is placed in the box through carelessness and subsequently leaks or becomes broken.

In Fig. 6 there is illustrated a modification employing a somewhat different partition for engaging the smaller ends of the eggs than that which has been described. Said partition is indicated at 9 and is provided with openings 9^a, through which the 30 upper ends of the eggs project. These openings are preferably circular in form, and around the same, the partition is provided with radial incisions 10 forming tongues 11. The tongues 11 are alternately 35 left flat and bent downwardly at an angle to the partition. If the eggs are of the ordinary size, the downwardly bent tongues will engage the small ends of the eggs as shown clearly in Fig. 6. If the eggs are unusually large, the flat tongues will be 40 bent upwardly, as shown at the extreme 45 right of Fig. 6.

In other words, while certain of the tongues 11 remain straight or flat so as to 50 more or less snugly fit the end of the egg, the alternate tongues are bent at an angle to engage the eggs at other points, and thereby provide a more secure and more resilient holding means than would be the 55 case were the tongues 11 bent at the same angle.

In Fig. 7, I illustrate a modification in which the tongues or fingers 8 of both partitions 3 and 4 project upwardly.

60 In Fig. 8, I illustrate a modification in which only one partition is employed and in addition to the two layers of excelsior arranged respectively above and below the

eggs, a filling of sawdust or similar granular material is used between the fingers 8 of 65 the partition.

In Fig. 9, a construction is shown employing a single partition as in Fig. 8, but using only a single packing material 18, preferably sawdust or some similar granular material. 70

Various slight changes might be made in the general form and arrangement of parts described without departing from my invention, and hence I do not limit myself to 75 the precise details set forth, but consider myself at liberty to make such changes and alterations as fairly fall within the spirit and scope of the appended claims.

What I claim as my invention, is: 80

1. In a shipping case for eggs, the combination with a receptacle formed of card board or similar material, of layers of resilient absorbent packing material adjacent opposite walls of said receptacle and a pair 85 of partitions between which the eggs are engaged, arranged between said layers of packing, and formed with openings for engagement by the ends of the eggs, tongues being struck out of said partitions in forming said openings, and occupying an angular relation to the partition to resist movement of the eggs parallel to the partitions and to hold the eggs fixed regardless of differences in the sizes of the eggs. 90

2. In a shipping case for eggs, the combination with a receptacle formed of card board or similar material, of layers of resilient absorbent packing material adjacent opposite walls of said receptacle, and a pair 100 of partitions between which the eggs are engaged, arranged between said layers of packing, and seated thereupon, said partitions being formed with openings for engagement by the ends of the eggs, said packing primarily resisting movement of the eggs transverse to the partitions, and the partitions resisting movements of the eggs parallel thereto. 105

3. In a shipping case for eggs, the combination with a receptacle formed of card board or similar material, of a partition member within said receptacle formed with openings for engagement by the eggs and having tongues struck out of said openings 110 and occupying angular relation to the partition to resist movement of the eggs parallel to the partition, a layer of resilient absorbent packing material interposed between said partition and the adjacent wall 115 of the closure, resisting movement of the eggs toward said wall, and resilient absorbent packing material resisting movement of the eggs toward the opposing wall. 120

In testimony whereof I affix my signature. 125
CARL R. SHAFFER.
